The ornamental design for a case, as shown and described.

DESCRIPTION

FIG. 1 is a front perspective view of a case showing my new design;
FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a top view thereof; and,

FIG. 8 is a front perspective view thereof.

The broken lines immediately adjacent the shaded surfaces represent boundaries of the claimed design. All other broken lines depict unclaimed environment. The broken lines form no part of the claimed design. The unshaded surface shown on the front of the case in FIG. 8 depicts an unclaimed electronic device housed within the case.
